UNITED STATES PATENT OFFICE

155,620

DESIGN FOR A BOAT

Grover I. Mitchell, Manchester, Conn.

Application February 5, 1948, Serial No. 144,299

Term of patent 14 years

(Cl. D71—1)

To all whom it may concern:

Be it known that I, Grover I. Mitchell, a citizen of the United States, residing at Manchester, in the county of Hartford and State of Connecticut, have invented a new, original, and ornamental Design for a Boat, of which the following is a specification, reference being had to the accompanying drawing, forming part thereof.

Fig. 1 is a plan view of a boat embodying my new design.

Fig. 2 is a side view thereof.

Fig. 3 is a perspective front view of said boat.

Fig. 4 is a rear view thereof.

Fig. 5 is an end view in vertical section on line 5—5 of Fig. 2.

I claim:

The ornamental design for a boat, substantially as shown.

GROVER I. MITCHELL.
